UNITED STATES PATENT OFFICE.

LUCIEN B. BOWIE, OF PHILADELPHIA, PENNSYLVANIA.

TRUSS.

Application filed October 7, 1921. Serial No. 506,114.

To all whom it may concern:

Be it known that I, LUCIEN B. BOWIE, a citizen of the United States, residing in Philadelphia, Pennsylvania, have invented 5 certain Improvements in Trusses, of which the following is a specification.

My invention relates to improvements in trusses, the object of my invention being to provide a truss of improved and novel form insuring comfort to the wearer and a proper support to the ruptured part. Another object of the invention is to provide a truss having no deteriorating corrodible parts. A further object is to provide novel and 15 improved means for attaching to the truss pad the straps by means of which the pad is secured to the body.

In the attached drawings:

Figure 1, is a view in perspective of the 20 pad with the straps detached;

Fig. 2, is a transverse section through the pad and the contiguous portions of the attaching straps illustrating the manner of securing the straps to the pad;

Fig. 3, is an outline view of a portion of the human body illustrating the manner in which the truss is applied;

Fig. 4, is a view in perspective of a modified form of the pad;

Figs. 5 and 6, are transverse sections of the pad illustrating modified means for securing the straps to the pad, and

Fig. 7, is a fragmentary perspective of 35 a portion of the straps illustrating the preferred method of attaching one strap to another.

With reference to Figs. 1, 2 and 3 of the drawings, the truss comprises a pad 1 having a substantially flat base portion 2, from the edges of which extends substantially at right angles to the plane of the base portion, a flange 3. In the present instance, the base portion 2 is substantially circular in form, the flange 3 extending around approximately 270° of the circumference thereof, and the base plate 2 comprises a portion 4 extending outwardly between the ends of the flange 3, which portion preferably is bent away from the plane of the said base 50 on the flanged side.

In the rear of the flange 3 is a pair of parallel slots 5, 5, and similar slots 6, 6, and 7, 7, are formed in the flange 3 at each side thereof. These slots provide a means for attaching the straps 8, 9 and 10, by means of

which the pad 1 is held in place against the ruptured part of the body.

As best shown in Fig. 2, the ends of the respective straps are inserted through the respective pairs of slots, the ends in the present instance being carried upwardly over the edge of the flange 3 so that the straps in passing over the flange will bear down upon their respective ends and clamp them firmly against withdrawal. This method of attaching the straps while entirely secure greatly facilitates attaching and detaching the straps to and from the pad.

The pad is intended to be applied in the manner illustrated in Fig. 3, the strap 10 passing down under the crotch and attaching at the back to one or other of the straps 9 and 8 which extend around the hips. The ends of the straps 8 and 9 may be secured together by any desired means, in the present instance there being employed a buckle 11 of aluminum, hard rubber or other non-corrodible material. The pad itself is preferably made of non-corrodible material, such as vulcanized rubber, aluminum or the like.

In the modification of Fig. 4, I have illustrated the flange 3^a corresponding to the flange 3 in the aforescribed pad extending completely around the periphery of the base plate 2^a, that portion of the flange lying uppermost when the pad is applied to the body being bent inwardly at the top towards the center of the pad to avoid the presentation of a sharp top edge to the abdomen when the body is bent forward. This form of pad has an advantage in the fact that the said upper portion of the flange 3^a provides an easy means for grasping the pad through the clothing to replace it in the event of possible displacement from the ruptured part.

In Fig. 5, I have illustrated a further means for securing the straps to the pad, in this instance a single strap 11 replacing the two straps 8 and 9, said strap 11 being passed through both pairs of side slots 6^a, 6^a, and 7^a, 7^a, and extending across the interior of the pad, the opposite free ends of the strap 11 being joined together in any suitable manner, as by means of a buckle 100 not shown. In this instance the strap 10^a which passes under the crotch is passed outwardly through the upper of the two slots 5^a and inwardly through the lower of the slots, 105 the free end lying in the interior of the pad,

this having been found an efficient way to secure the end of the strap to the pad.

In Fig. 6, a still further method of securing the straps is illustrated, this method lending itself particularly to the elimination of all buckles or other securing means for the straps. In this instance a single strap 12 replaces the aforesaid straps 8 and 9 in the same manner as does the strap 11 of the 10 aforescribed modification, but in this instance the free ends of the strap 12 are passed, as shown, outwardly through the upper of the pairs of slots 6^a, 6^a, and 7^a, 7^a, and inwardly into the interior of the pad through 15 the lower of these pairs of slots, thereby forming a closed loop which, in applying the truss to the body, may be passed over the head or upwardly around the legs. In this 20 instance the crotch strap 10^b is in the form of a single strap doubled on itself with the 25 free ends inserted through the slots 5^a, 5^a, as clearly shown, one end of the strap having previously been passed through a pair of slits 13 and 14 formed in a loop 15 of a material wider than the strap 10^b, said loop being passed over the strap 12 and securing the strap 10^b thereto. It will be noted that 30 in this modification no buckle or other securing means is required, nor any stitching of the retaining straps.

The truss has been found to possess numerous advantages over the types in general use. As previously described, the base 2 is substantially flat, or it may be convexed to 35 conform to the curve of the body, so that while providing a firm holdback for the rupture, there is nothing projecting into the rupture and tending to separate the muscles. By employing the flange 3 over the top edge 40 of which the straps pass, a greater leverage is obtained than were the straps attached directly to the sides of the base portion 2, this additional advantage insuring a firm pressure of the pad against the rupture. Further the upturned portion 4 of the part 2 or 45

the inturned portion of the flange 3^a presents a curved surface to the body, and prevents the edges of the base portion from digging into the flesh.

Furthermore, and as previously described, the method of attaching the straps to the pad greatly facilitates their removal and the application of other straps, and since these parts worn continually against the body quickly become foul, this will be recognized as a point of great advantage. The pad itself is of extremely simple form and easily cleaned, and by employing a number of sets of straps, it is possible to quickly and easily apply a new, clean set in place of a 50 set removed for cleaning purposes. The extreme simplicity of the device is also pointed out with the corresponding manufacturing advantages, and the entire absence of any 55 corrodible metal or of rigid parts other than 60 the pad insures comfort. It is also to be noted that with this pad and the particular form of securing means, it is possible to eliminate buckles or other securing means, the securing means being an integral part 65 of the pad. In this manner, the number of individual parts of the truss and consequently the cost are materially reduced.

Numerous changes in form and in the arrangement of elements will present themselves, and it is to be understood that the right is reserved to all modifications within the scope of the invention.

I claim:

A truss comprising a pad having a substantially flat working face and a substantially annular flange extending backwardly from the edge of said face, said flange over a portion of its circumference being substantially perpendicular to the working face and over the remainder of its circumference being inclined inwardly, substantially as described.

LUCIEN B. BOWIE.
